FAUCET FIXTURE

Joseph N. Pugliese, Compton, Calif.

Filed Feb. 19, 1965, Ser. No. 83,905

Term of patent 14 years

(Cl. D91—3)

FIG. 1

FIG. 3

FIG. 1 is a perspective view of a faucet fixture showing my new design;

FIG. 2 is a top plan view thereof; and

FIG. 3 is a side elevational view showing the left hand side thereof with respect to FIGS. 1 and 2, the opposite side being a mirror image thereof.

I claim:

The ornamental design for a faucet fixture, substantially as shown and described.
